UNITED STATES PATENT OFFICE

EDGAR J. THOMPSON, OF MONTREAL, QUEBEC, AND RAYMOND H. HUBLER, OF SHERBROOKE, QUEBEC, CANADA, ASSIGNEES TO CANADIAN SILK PRODUCTS LIMITED, OF SHERBROOKE, CANADA, A CORPORATION OF QUEBEC

APPARATUS FOR KNITTING FULL FASHIONED HOSIERY

Application filed May 28, 1928. Serial No. 281,246.

This invention relates primarily to the knitting of full fashioned hosiery and more particularly to the incorporation of ornamental devices or designs in the knitted fabric, such as in the heel portions of fanciful design, clocks and other like ornamentation, having irregular contours.

The principal object of the invention is to provide a new and improved apparatus for making possible the knitting of a greater variety of these designs on full fashioned knitting machines of the "Cotton" type than has been possible in the past.

A further object is to provide new and improved mechanism which will permit of greater precision in the formation of the various designs, and which can be easily and quickly adjusted when desired.

A further object is to provide a mechanism which can be incorporated in a standard full fashioned machine with minimum disturbance of the parts, and the cost of installing of and subsequent maintenance of which will be comparatively small.

To this end the invention consists of the combination, construction and particular arrangement of the parts hereinafter described and illustrated and pointed out in the claims.

For full comprehension of the invention reference should be had to the accompanying drawings in which corresponding reference characters indicate the same parts in all the views.

Figure 1 is a fragmentary plan view of a standard full fashioned knitting machine showing the application of the invention thereto.

Figure 2 is a vertical sectional view taken on line 2-2 Figure 1.

Figure 3 is a vertical sectional view taken on line 3-3 Figure 1 and drawn to a larger scale.

Figure 4 is a similar view to Figure 2 but drawn to a larger scale and illustrating particularly the ratchet mechanism for operating the abutment drum.

Figure 5 is a rear elevation.

Figure 6 is a detail plan view of one of the chain elements for actuating the abutment drum ratchet mechanism.

Figure 7 is a sectional view taken on line 7-7, Figure 6.

Figures 8, 9, 10 and 11 are diagrammatic views of some of the various heel contours obtainable with the present invention, Figure 8 showing the conventional pointed design with straight inclined stepped sides, Figure 9 showing a heel design with concave sides, Figure 10 showing a design with convex sides and Figure 11 showing a design combining both concave and convex portions.

Figure 12 is a diagrammatic plan view of a portion of a stocking leg having heel portions with concave contours.

The drawings illustrate the preferred embodiment of the invention in a standard full fashioned machine and, as the general construction of machines of this type is well known in the art, only those parts of the machine that are necessary for full comprehension of the invention are shown.

Referring to these drawings, the main frame of the machine is indicated at 2, the main cam shaft which extends throughout the length of the machine at 3, two adjoining sections or banks of needles in diagram at 4 and 5 respectively, thread carrier rods at 6, 7 and 8 respectively, thread carriers at 9, 10, 11, 12, 13 and 14 respectively. The carrier rod reciprocating mechanism is of usual construction and consequently is not shown.

The function of the thread carriers, as is well known in the art, is to feed the yarn to the individual needle banks, the carrier rods 6, 7 and 8 travelling longitudinally in a reciprocal manner and moving the thread carriers back and forth across the needle banks, the free ends of the carriers extending downwardly to within close proximity of the needles. In the illustrated embodiment the thread carriers 13 and 14, which are mounted upon the carrier rod 8, have the maximum travel as they supply yarn to the needles for the full width of the fabric, whereas thread carriers 9 and 10, which are mounted on carrier rod 6, and carriers 11 and 12, which are mounted on rod 7, supply splicing or reinforcing thread such as is used in the heel portions of the stockings.

and their travel, during the heel forming operation, is limited to a predetermined number of needles in each bank or section, the heel portions being produced in halves as is well known in the art.

As hereinbefore stated, the present invention relates to the incorporation of ornamental designs in the fabric during the initial knitting operation and more particularly to the formation of heel portions having irregular or fanciful outlines. Heretofore many attempts have been made to produce full fashioned hosiery with fanciful heel designs on straight knitting machines of the "Cotton" type but, in most instances, these designs have only involved straight line contours such as the well known "pointed" heel designs that have been produced for some time. The purpose of this invention is to provide new and improved apparatus which will make possible the production of ornamental designs of this nature having curved as well as straight line contours on knitting machines of the aforementioned type. To this end, new and improved means is provided for automatically determining the extent of travel of each splicing thread carrier for each course as the knitting operation progresses, such means consisting of co-acting elements so constructed and arranged that curved or straight line contours may be produced through simple adjustments.

This improved means comprises a duplex abutment drum rotatably mounted upon a horizontal axis in a fixed bracket overhanging the carrier rods, longitudinally adjustable stops on the rods, ratchet and pawl mechanism for intermittently rotating the drum, variable means for timing the operation of the ratchet and pawl mechanism and means for synchronizing the last-mentioned means with the carrier rod reciprocating mechanism.

The abutment drum consists of spaced collars 16 and 17 united by a stub shaft 18 extending horizontally through the fixed bracket 19. These collars are rotatable as a unit and their outermost ends are provided with irregular abutment faces 20 and 21. In the illustrated embodiment, these faces are of spirally stepped form and they are so arranged that, when the drum is rotated, the steps are successively moved to positions obstructing the path of travel of stops 22 and 23, mounted upon and movable longitudinally in unison with carrier rods 6 and 7, the stops being threaded through brackets 22^a and 23^a for longitudinal adjustment relatively to these rods. The collars thus constitute automatically variable abutments which limit the inward reciprocal travel of the carrier rods and their respective thread carriers. In the illustrated embodiment they are precisely alike but are relatively reversed, this being essential owing to the

fact that collar 17 limits inward travel of thread carriers 9 and 10 which supply splicing to the needles for forming the left half portions of the heel, while collar 16 limits the inward travel of thread carriers 11 and 12 which supply the splicing for the right half heel portions. It will be seen therefore that, when the carrier rods are reciprocated, the extent of travel of carrier rod 6 towards the left, viewing the machine in front elevation, and of carrier rod 7 towards the right will be determined by the location of the abutment faces 20 and 21 relatively to the stops, minimum travel taking place when the points of greatest width of the collars are directly in longitudinal alignment with the stops and maximum travel occurring when the narrowest width is positioned at these contact points. It is obvious therefore that the number of needles, supplied with splicing for each individual course, may be varied by rotation of the drum.

This rotation is intermittently effected through ratchet mechanism consisting of a circumferential series of ratchet teeth 24 on collar 17, a ratchet pawl 25 adapted to engage the teeth, and a vertically disposed rocker arm 26 hingedly mounted at its lower end as at 27 in a bracket 28 and pivotally carrying the pawl at its upper end as at 29. The rocker arm has a lateral projection 30 which normally bears upon the top of a fixed pin 31 and it is yieldingly retained in this position by a helical spring 32. The free end of the projection is rounded off as at 33 and constitutes a trip which co-acts with the variable means for actuating the ratchet mechanism at predetermined intervals. This variable means consists of an endless sprocket chain 34 carrying as a component part thereof a series of spaced externally projecting elements 35 which are arranged to successively engage the trip 33 and through it intermittently rock the arm 26. The chain is looped successively around sprocket wheel 36 located directly in rear of the rocker arm and in close proximity thereto, sprocket wheel 37 mounted in a rearwardly extending bracket 38 on the main frame, sprocket 39 to be presently described and a sheave 40, which is deeply flanged to accommodate the projections without fear of displacement. It is important that the chain be kept taut during its travel as the spacing of the elements 35 has an important bearing on the main knitting operation. Any preferred means for obtaining this result may be employed, that illustrated consisting of a counter weight 41 which is suspended from the chain through sprocket 39 and at the same time acts as a bearing for the latter. The projections 35, which may be termed the course measuring elements, as they determine the number of courses knitted for each change of longitudinal travel of the splicing carriers, con-

stitute component parts of the sprocket chain, each consisting of a link detachably incorporated in the chain and having a projecting cross web 35a presenting an inclined cam surface 35b which serves to displace the 5 rocker arm as it travels past the same.

The spacing of these course measuring elements determines the number of courses knitted for each step of the drum, the travel 10 of the chain being synchronized with the reciprocatory travel of the carrier rods by mechanism to be presently described, hence it is obvious that variations in the contour 15 of the heel design will be proportional to variations in the spacing of the elements, provided of course that the longitudinal distance between the abutment faces of the successive steps of the drum is constant. In the illustrated embodiment, in which the 20 drum is uniformly stepped spirally, each step represents a change in length of travel of the thread carriers. If, therefore, the spaces between the chain elements are of equal length, a stepped heel contour will be knitted 25 such as illustrated in diagram in Figure 8, forming the straight "pointed" heel of conventional design. If, on the other hand, the length of the successive spaces is progressively decreased or progressively increased, 30 a concave or a convex heel contour, such as illustrated in Figures 9 and 10, respectively, will be the result. It is obvious, therefore, that a wide variety of designs may be produced through the simple expedient of adjusting the spacing of the elements relatively 35 to one another.

The sprocket chain is actuated and its travel is synchronized with the reciprocatory action of the carrier rods by cam 43 fixed on 40 shaft 3 and rotatable in unison therewith, rocker arm 44 fulcrumed approximately midway its length on the main frame as at 45 and at one end carrying an anti-friction roller 46 for engagement with the cam, a 45 vertically disposed connecting rod 47 operatively connecting the opposite end of the arm 44 to the free end of a ratchet lever 48, a ratchet wheel 49 keyed upon the shaft 50 carrying sprocket wheel 36, and a pawl 51 50 pivotally carried by the lever 48 and adapted to mesh with ratchet 49. The shaft 3 is operatively connected to the carrier rod reciprocating mechanism in the usual manner, the shaft making one complete revolution for 55 each reciprocation of the carrier rods so that the travel of the chain is synchronized with the travel of the rods. In the operation of the foregoing chain actuating mechanism, the cam 43 is arranged to intermittently actuate ratchet 49 and, consequently, to intermittently rotate sprocket wheel 36. When 60 the splicing carriers are not functioning, the pawl 51 may be moved to position out of engagement with ratchet 49, as indicated in 65 dotted lines in Figure 2, the sprocket shaft

50 being yieldingly held against rotation by a pin 52 which engages a notched escapement wheel 53 keyed upon the end of the shaft opposite to that carrying the ratchet. This 70 end of shaft 50 also carries a two-part clutch 75 for manually rotating the shaft when it is desired to adjust the position of the chain, one clutch part 55 being keyed on the shaft and the other 56 being rotatably free thereon and movable axially relatively thereto, a 80 small crank handle 57 being formed integrally with the last-mentioned part. The pin 52 is slidably mounted in the bearing bracket 58 and its upper end protrudes therefrom and carries a cam 59, which when 85 turned withdraws the pin from engagement with the wheel, the top of the bracket having a cam surface 60 corresponding with that of the cam. A spring 61 yieldingly maintains the pin in wheel engaging position. 85

Operation

During the knitting of the leg portion to points A—A, see Fig. 12, on the fabric, the heel forming mechanism is inactive, pawl 90 51 being out of engagement with ratchet 49 and the splicing thread carriers being idle. When points A—A are reached however, the heel forming mechanism is brought into action, the pawl being moved into engagement 95 with its ratchet wheel and the splicing thread carriers set in motion. At the commencement of this heel forming operation, the abutment drum should, in the present embodiment, be positioned with its points 100 of greatest width intersecting the paths of travel of the stops 22 and 23, and the chain should be positioned with the first of the series of course measuring elements 35 at a predetermined distance of travel from trip 105 33, this distance being determined by the number of courses to be knitted by the splicing thread carriers before a change in the extent of their reciprocatory travel is desired. This relative positioning having 110 been attained and the machine set in motion, the splicing thread carriers 9 and 10, which are located at the outermost points of their travel relatively to the fabric, move in an inward direction supplying yarn to 115 only a small group of needles adjacent the ends of each bank, the movement terminating when stop 23 contacts with the abutment collar 17. The movement of the thread carriers 13 and 14 continues however 120 for the full width of the fabric, the usual sliding frictional connection between the various carrier rods and their actuating means permitting stoppages of any of the rods at any point throughout the maximum travel without in any way affecting one another. On the return movement the splicing thread carriers 11 and 12 also come into 125 action and their operation is precisely the same as that of the thread carriers 9 and 130

10, the inward travel being terminated by the engagement of stop 22 with abutment collar 16. On this return movement the thread carriers 9 and 10 and 13 and 14 return to 5 their starting points, the reciprocal movements of the various carrier rods relatively to one another being timed by means well known in the art. These reciprocal movements of the thread carriers continue to 10 points B—B on the fabric, the stops 22 and 23 functioning on alternate reciprocations, and the abutment drum, being intermittently rotated by the travel of the endless chain, the movement of which is synchronized with 15 the action of the carrier rods through cam 43 as hereinbefore pointed out. When the points B—B on the fabric have been reached, rotation of the abutment drum is automatically stopped by the simultaneous arrival of 20 a smooth external portion 70 located within the circumferential series of drum ratchet teeth, this portion rendering the pawl 25 inactive in so far as the drum is concerned. If desired, the pawl 51 may be moved manually 25 out of engagement with ratchet 49 to eliminate further travel of the chain, the latter having completed its function. Continued operation forms the heel flaps of the 30 fabric, stops 22 and 23 continuing to engage the abutment drum alternately but the latter remaining idle.

In order to prevent the abutment drum from exceeding the normal rotation given it by pawl 24, collar 17 is provided with an 35 external band 71 and a braking strip 72, of felt or any other suitable material, is held in frictional engagement therewith by a bracket 73 having a portion curved concentrically with the periphery of the band.

The illustration and description of only 40 two adjoining sections or banks of needles has been adopted for purposes of brevity, being thought to be sufficient for a full comprehension of the invention and it is presumed to be obvious that all the sections or 45 banks of needles of the entire machine can be controlled from the one abutment drum, the latter and its associated parts being located at any point throughout the length 50 of the machine found to be preferable.

It should also be pointed out that no attempt has been made herein to illustrate the 55 extensive variety of designs that the present invention makes possible, those specifically referred to being thought sufficient for present purposes.

What we claim is as follows:

1. In a machine of the type described, reciprocal thread carriers, an intermittently rotatable stepped abutment for varying the length of reciprocal travel of the carriers at predetermined course intervals, an endless chain, a series of spaced cam elements carried by said chain, ratchet mechanism adapted and arranged to be intermit-

tently actuated by said elements to turn said abutment, and means for driving said chain.

2. In a machine of the type described, reciprocal thread carriers, an intermittently rotatable stepped abutment for varying the length of reciprocal travel of said carriers at predetermined course intervals, ratchet mechanism for intermittently rotating the abutment, a trip device forming a component part of the said mechanism, an endless chain, a series of spaced cam elements carried by said chain in a path intersected by said trip, whereby said ratchet mechanism is intermittently rotated to turn 70 said abutment at course intervals determined by the spacing of said cam elements and means for driving said chain in unison, with the reciprocation of said thread carriers.

3. In a machine of the type described, reciprocal thread carriers, a rotatable stepped abutment for varying the length of reciprocal travel of said carriers at predetermined course intervals, ratchet mechanism for intermittently rotating said abutment, said mechanism consisting of a ratchet wheel forming a component part of said abutment, a normally stationary pawl, a rocker carrying said pawl in operative engagement with said ratchet wheel, a trip on 90 said rocker, an endless chain, a series of spaced cam elements carried by said chain and adapted to successively engage said trip, and actuate said pawl, each displacing movement of the pawl rotating the abutment to a limited extent, and means for driving said chain in timed relation with the reciprocation of said thread carriers.

4. In a machine of the type described, reciprocal thread carriers, an intermittently rotatable stepped abutment for varying the length of reciprocal travel of the carriers at predetermined course intervals, and a series of spaced travelling cam elements constructed and arranged to drive successively to a limited extent the abutment at course intervals determined by the relative spacing of the elements, a continuously rotating driving shaft, means for intermittently driving the said elements synchronously from said shaft, and means for manually driving the said elements independently of the first mentioned driving means substantially as described.

5. In a machine of the type described, reciprocal thread carriers, a rotatable stepped abutment for varying the length of reciprocal travel of the carriers at predetermined course intervals, stops on the carriers constructed and arranged to engage 125 the stepped portions of the abutment, a circumferential series of ratchet teeth on said abutment, a rocker arm fulcrumed in fixed position adjacent thereto, a pawl pivotally mounted upon said arm and in engagement 130

with the said teeth, a laterally projecting trip on said arm, a stop limiting movement of the arm away from the abutment, means yieldingly retaining the trip in engagement with said stop, a sprocket wheel located adjacent to the said trip and rotatable on an axis in parallelism with the axis of the abutment, an endless sprocket chain looped over said sprocket wheel, a series of spaced cam elements on said chain, said elements being constructed and arranged to travel in a path intersected by said trip to drive the ratchet and intermittently rotate said abutment, a ratchet wheel keyed upon said sprocket shaft, a ratchet lever fulcrumed at one end on said shaft, a pawl pivoted on said lever and adapted to assume positions in or out of engagement with said ratchet wheel, a continuously rotating driving shaft, a cam on said shaft, a rocker arm fulcrumed adjacent thereto and adapted to be actuated by the cam, a connecting rod effecting an operative connection between said rocker arm and ratchet lever, means for driving said chain manually consisting of clutch members on said sprocket shaft, one fixed thereto and the other free, and a crank arm on said free member, and escapement means yieldingly controlling the travel of said chain, said last mentioned means consisting of a notched wheel fixed on said sprocket shaft and rotatable therewith, and a spring impelled plunger pin slidably mounted in fixed position adjacent the notched wheel and adapted to yieldingly fit into the notches therein. 95

6. In a machine of the type described, horizontally disposed reciprocatory thread carriers, stops on the carriers, a bracket overhanging said carriers, a shaft extending horizontally through the bracket and rotatable therein, an intermittently rotatable duplex abutment for varying the length of reciprocal travel of the carriers at predetermined course intervals, said abutment consisting of collars mounted upon the respective ends of said shaft and rotatable in unison therewith, each collar having a stepped abutment face limiting the travel of one of the said stops, one of the said collars having a circumferential series of ratchet teeth, a rocker arm fulcrumed adjacent the said teeth, a pawl carried by said arm in operative engagement with the teeth, a trip device on said arm, a sprocket wheel located adjacent said trip device, an endless sprocket chain looped over said sprocket wheel, a series of spaced cam elements on said chain and constructed and arranged to successively engage said trip device to drive the ratchet to intermittently rotate said abutment, and means for driving said chain, substantially as described. 110

7. In a machine of the type described, horizontally disposed reciprocatory thread carriers, stops on the carriers, an intermittently rotatable stepped abutment located adjacent the carriers substantially midway the length thereof in the paths of the stops for varying the reciprocal travel of the carriers at predetermined course intervals, ratchet mechanism for rotating said abutment, a trip device forming a component part of said mechanism, a horizontally disposed shaft located in juxtaposition with the axis of the abutment, a sprocket keyed on said shaft, an endless sprocket chain looped over said sprocket, a series of cam elements on said chain adapted to travel in a path intersected by said trip to actuate said ratchet mechanism, means for intermittently driving said chain, means for independently driving said chain manu- 130

ally, consisting of clutch members on said sprocket shaft, one fixed thereto and the other free, and a crank arm on said free member, and escapement means yieldingly controlling the travel of said chain, said last mentioned means consisting of a notched wheel fixed on said sprocket shaft and rotatable therewith, a spring impelled plunger pin slidably mounted in fixed position relatively to the notched wheel and adapted to yieldingly engage the notches therein, and means for at times releasing the wheel from said pin, substantially as described.

Signed at the city of Sherbrooke, Province of Quebec, Canada, this third day of May, 1928.
